(57) **CLAIM**

The ornamental design for a fluorescent lamp tube, as shown and described.

DESCRIPTION

FIG. 1 is a front perspective view of fluorescent lamp tube showing my new design; Wherein the broken line in the drawing is included for the purpose of illustrating environmental detail and forms no part of the claimed design.

FIG. 2 is a front view thereof.

FIG. 3 is a rear view thereof.

FIG. 4 is a side view thereof.

FIG. 5 is a top view thereof; and,

FIG. 6 is a bottom view thereof.
